UNITED STATES PATENT OFFICE.

WILKENS A. SCHENCK, OF ALLEGHENY, PENNSYLVANIA.

VICE.

No. 839,039.

Specification of Letters Patent.

Patented Dec. 18, 1906.

Application filed April 19, 1906. Serial No. 312,709.

To all whom it may concern:

Be it known that I, WILKENS A. SCHENCK, a citizen of the United States, residing at Allegheny, in the county of Allegheny and State of Pennsylvania, have invented new and useful Improvements in Vises, of which the following is a specification.

My invention relates to improvements in pattern-makers' and other vises of the quick-adjustment type, and particularly to that variety wherein a screw for adjusting the movable jaw is employed in conjunction with a split nut the sections of which normally engage the screw to hold the adjustable jaw in position and permit it to be adjusted thereby toward and from the fixed jaw, and which nut-sections may be disengaged from the screw to adapt the movable jaw to be manually adjusted to engage the work and then thrown into engagement with the screw for a finer adjustment of the movable jaw to firmly clamp the work.

The object of the present invention is to provide a vise of this type which embodies improved means for operating the nut-sections, which means permit the movable parts of the vise to be operated in a more convenient and efficient manner and at the same time produce a construction which is simple and may be manufactured at a comparatively low cost.

With this and other objects in view the invention consists of the features of construction, combination, and arrangement of parts hereinafter fully described and claimed, reference being had to the accompanying drawings, in which—

Figure 1 is a side elevation of a vise embodying my invention. Fig. 2 is a top plan view of the same. Fig. 3 is a central vertical longitudinal section. Fig. 4 is a cross-section on line 4-4 of Fig. 3. Fig. 5 is a detail perspective view of the depressible hand-piece, and Fig. 6 is a detail elevation of the end bearing or cross piece. Fig. 7 is a view similar to Fig. 3, showing a modification in the construction of the split nut and means for operating the actuating-rod. Figs. 8 and 9 are cross-sections on the line 8-8 of Fig. 7, showing the split nut in engagement with and disengaged from the split shank; and Fig. 10 is a detail view of the forward or operating end of the actuating-rod.

The numeral 1 in the drawings designates a fixed frame carrying a fixed or stationary jaw 2 and comprising a horizontal plate 3,

carrying downwardly-projecting side pieces 4, terminating in lateral extended flanges 5, pierced for the passage of suitable fastening devices to secure said fixed frame to a work-bench or other support. The fixed frame is further provided with a front wall 6, corresponding in depth to the sides 4, and a short rear wall 7.

Cooperating with the fixed frame 1 is a sliding frame comprising side guide rods or bars 8, connected at their forward ends by a cross piece or head 9, which is extended upwardly to form a movable jaw 10, and at their rear ends by a cross piece or head 11. (Shown in detail in Fig. 6.) The guide-rods 8 slide in openings formed in the walls 6 and 7 of the frame 1, and these walls are further provided with openings 12 for the passage of an adjusting-screw 13, terminating at its forward end in a sleeve 14 to receive the usual sliding actuating-handle 15, and provided at its rear end with a cylindrical stem 16, which fits and turns in a bearing-opening 17, formed centrally in the head 11, and is provided with a key 18 to hold it from displacement. The forward portion of the screw has a cylindrical journal 19, which turns in a bearing-opening 20 in the head 9 and is provided with a collar 21, abutting against the forward surface of said head to impart pressure to said head and adjust the movable jaw toward the fixed jaw 2. The terminals of the threaded portion of the screw abut, respectively, against the two heads 9 and 11 to hold the screw from end-wise movement and to adjust the head 9 and movable jaw away from the fixed jaw. The outer or rear ends of the rods 8 may be connected to the head 11 in any preferred manner, said head being shown in the present instance as being provided with end openings 17 to receive the contiguous ends of the rod, which may be fixed therein in any preferred manner.

In the housing formed by the walls of the frame 1 is a split nut comprising semicircular sections 22 and 23, which are provided upon their lower faces with downwardly-projecting angular lugs 24 and 25, formed with correspondingly-shaped slots 26 and pivoted at their lower ends beneath the lower terminals of the slots upon pivot pins or bolts 27, engaged with the front wall 6. The nut-sections normally engage the screw and lock the sliding frame, and consequently the movable jaw, from sliding movement, while permitting said frame and jaw to be adjusted in the

ordinary manner through the medium of the screw. When the nuts are in engaging position, the inner arms of their lugs extend downwardly in a true vertical plane, while 5 the outer arms of said lugs project oppositely at an oblique angle thereto and in divergent relation, as clearly shown in Fig. 4, the slots 26 therein, which conform to the shape of the lugs, being correspondingly arranged, so 10 that their oblique portions overlap one another. Extending through an opening 28, formed in the wall 6 below the screw and above the pivot-bolts 27, is a nut-actuating rod 29, which passes through the slots 26 in 15 the lugs and is suspended at its front and rear ends from links 30, carried by the heads 9 and 11, the forward end of the rod supporting an operating device comprising a depressible handpiece 31, disposed upon the forward end of the rod between the sleeve 14 and head 9 and provided with a stirrup-shaped body portion 32, the arms of which straddle or extend downward on opposite sides of the screw and are joined at their free 20 ends and fastened to the rod. Normally the links 30 project at a downward and forward angle, as shown in Fig. 3, and are adapted when the handpiece 31 is depressed to be swung to a vertical position, thereby depressing the rod 29 and giving it a rearward sliding movement. As shown in Fig. 4, when the nut-sections 23 are in engagement with the screw the rod 29 lies in the upper offset portions of the slots 26 in the lugs 24 and 25, thereby locking the nut-sections against 25 movement, so that when the rod is depressed in the manner described it will be forced downwardly in said slots and engage the walls thereof, and thereby swing the lugs outwardly or laterally. This action will throw 30 the nut-sections 22 and 23 out of engagement with the screw 13, and thereby unlock the sliding frame, permitting the same to be slid rearwardly to adjust the movable jaw to engage 35 the work, as will be readily understood. This operation, it will be clear, may be performed by employing one hand to depress the handpiece 31 and using the other hand to place the work in the desired position between 40 the jaws of the vise, thus enabling the operator to perform this adjustment in a simple and convenient manner. This quick adjustment of the movable jaw is employed to bring it into engagement with the work and expedite the adjusting operation, and after the jaw has been so adjusted the handpiece 31 is released, thus permitting the rod 29 to swing back to its normal position. In so swinging back the rod will move upwardly 45 and in the slots 26 in the lugs 24 and 25 and restore said lugs to their normal position, thereby again throwing the nut-sections into engagement with the screw, permitting the latter to be turned, by means of its actuating handle 15, to adjust the jaw for finer adjust-

ment to clamp the work firmly against the fixed jaw 2.

It will be observed that the lugs 24 and 25 with their peculiar form of slots constitute, in effect, and perform the function of cams or eccentrics, which are operated through the movement of the rod 29 to throw the nut-sections into and out of engagement with the screw. This simple form of nut-operating means reduces the cost of construction over existing devices to a considerable extent and enables the device to be cheaply manufactured.

In the modification of the invention shown in Figs. 7 to 10, inclusive, the nut-sections 22' and 23' are provided with straight depending lugs 24' and 25', pivotally mounted at their lower ends upon a common pivot-pin 27', and said lugs are formed with angular slots 26', corresponding in form to the slots 26 shown in Fig. 4, except that the obliquely or angularly projecting ends of these slots are located at the upper ends of the lugs. The nut-sections 22' and 23' are further provided at their upper ends with lugs or ears 22^a and 23^a, socketed to receive the ends of an expansive spring 23^b, the terminal portions of which are suitably attached to said lugs, so that the spring will normally act by expansion to force the nut-sections apart and when compressed by the closing of said nut-sections will fold into the sockets and permit the nut-sections to lie closely together. By this construction the downward and rearward movement of the actuating-rod 29' will cause the nut-sections to be closed against the resistance of the spring 23^b, while upon the release of said rod the spring will expand and restore the nut-sections and rod to their normal positions. The rod is provided at its forward end in this embodiment of the invention with a hook-shaped finger-piece 31', lying below the forward end of the actuating-screw, and the supporting-links 30' are so arranged that an upward movement of the finger-piece will cause the rod to swing upwardly and rearwardly, thereby to close the nut-sections.

Having thus described the invention, what is claimed as new is—

1. In a vise, the combination of jaws, one movable toward and from the other, a sliding frame carrying the movable jaw, a screw for operating said sliding frame, a sectional nut for locking said screw against movement, the sections of the nut being provided with cam-slots, and an actuating device movable in said slots to effect the movement of the nut-sections into and out of engagement with the screw.

2. In a vise, the combination of a stationary frame carrying a fixed jaw, a sliding frame carrying a co-operating jaw, a screw journaled in the sliding frame and movable through the stationary frame, a sectional nut,

angular lugs carrying the nut-sections and pivoted to the stationary frame, said lugs being provided with angular slots, a rod extending through said slots and operative therein for swinging said lugs to throw the nut-sections into and out of engagement with the screw, and means for operating said rod.

3. In a vise, the combination of a stationary frame carrying a fixed jaw, a sliding frame carrying a coöperating jaw, a screw journaled in the sliding frame and movable through the stationary frame, a sectional nut, lugs carrying the nut-sections and pivoted to the stationary frame, said lugs being provided with angular slots, a rod extending through said slots and operative therein for swinging said lugs to throw the nut-sections into and out of engagement with the screw, links suspending said rod from the sliding frame, and means for swinging said rod upon the links to throw the nut-sections into and out of engagement with the screw.

4. In a vise, the combination of a stationary frame carrying a fixed jaw, a sliding frame carrying a coöperating jaw, a screw journaled in the sliding frame and movable through the stationary frame, a sectional nut, lugs carrying the nut-sections and pivoted to the stationary frame, said lugs being provided with angular slots, a rod extending through said slots and operative therein for swinging said lugs to throw the nut-sections into and out of engagement with the screw,

means for movably supporting the rod from the sliding frame, and a handpiece connected to said rod and arranged in juxtaposition to the movable jaw. 35

5. In a vise, the combination of a stationary frame carrying a fixed jaw, a movable jaw slidably supported by said frame, a screw-shaft for actuating the movable jaw, a split nut carried by the movable jaw and comprising pivoted sections adapted to engage the screw-shaft to lock the same thereto, said sections being provided with angular slots, 45 an actuating-rod passing through and movable in said slots, and means for actuating the rod. 40

6. In a vise, the combination of a stationary frame provided with a fixed jaw, a movable jaw, a screw-shaft carried by the frame for operating the said movable jaw, a split nut carried by the movable jaw and comprising sections pivotally mounted and adapted to engage the screw-shaft, said sections being formed with angular slots, a spring for holding the nut-sections open, and means coacting with said slots to close the nut-sections against the resistance of said spring. 50 55 60

In testimony whereof I affix my signature in presence of two witnesses.
